US0D1093428S

(12) **United States Design Patent** (10) Patent No.: **US D1,093,428 S**
(45) Date of Patent: ** Sep. 16, 2025

(54) **PROPELLER FOR SHIPS**

(71) Applicant: **GUANGDONG EPROPULSION TECHNOLOGY LIMITED**,
Dongguan (CN)

(72) Inventors: **Youquan Yuan**, Guangdong (CN);
Zeyuan Xuan, Guangdong (CN);
Qiang Wang, Guangdong (CN)

(**) Term: **15 Years**

(21) Appl. No.: **35/522,712**

(22) Filed: **Oct. 16, 2023**

(80) **Hague Agreement Data**

Int. Filing Date: **Oct. 16, 2023**

Int. Reg. No.: **DM/232770**

Int. Reg. Date: **Oct. 16, 2023**

Int. Reg. Pub. Date: **Oct. 18, 2024**

(51) LOC (15) Cl. **15-01**

(52) U.S. Cl.

USPC **D15/4**; D12/317

(58) **Field of Classification Search**

USPC D15/4, 5; D12/300-318

CPC B63H 20/007; B63H 25/02; B63H 20/32;

H02K 1/187; H02K 5/203
